UNITED STATES PATENT OFFICE

LAWRENCE B. WILSON, OF TUCSON, ARIZONA

TWO PART COUCH

Application filed April 21, 1932. Serial No. 606,676.

This invention relates to a two part couch, the general object of the invention being to so form the two parts that the couch can be placed in various positions and said two parts 5 associated with each other to form various shapes by making the parts of L-shape with the limbs of each part of such proportions that a limb of one part can fit in the space formed by the two limbs of the other part, so as to make a rectangular shaped article.

This invention also consists in certain other features of construction and in the combination and arrangement of the several parts to be hereinafter fully described, illustrated in 15 the accompanying drawings and specifically pointed out in the appended claim.

In describing the invention in detail, reference will be had to the accompanying drawings wherein like characters denote like or 20 corresponding parts throughout the several views, and in which:—

Figure 1 is a perspective view of one of the parts.

Fig. 2 is a top plan view showing the parts 25 so placed together as to form a rectangular face.

Fig. 3 is a top plan view showing the two parts arranged to form a channel shaped couch.

Fig. 4 is a view showing the two parts 30 separated with the table placed between them.

Fig. 5 is a plan view showing how one part can be placed in the corner of a room.

As shown in these views, the couch is 35 formed of two L-shaped parts A and B with the long limbs of the two parts of the same length and the widths of said long limbs being equal to the lengths of the adjacent short limbs. Thus a limb of one part will fit in the 40 space formed by the other part to provide a couch of rectangular shape as shown in Fig. 2. Or as shown in Fig. 3, two similar limbs of the two parts can be placed in end to end relation to form a couch of channel shape in 45 plan view so that the couch can be placed adjacent a fire place.

Fig. 4 shows the two parts separated with a table C placed between them so that four 50 persons can sit around the table on the two parts of the couch with a person at each side

of the table. This is desirable when playing cards or the like.

Fig. 5 shows one of the parts of the couch placed in a corner of a room.

As shown, each part consists of a body part 55 1 supported on the short legs 2 and having a cushion 3 resting on the top of the body part, this cushion being of course of the same shape as the body part.

When the parts are arranged as shown in 60 Fig. 2, the couch can be used as a bed. This invention provides an economical way to furnish either a living room or a den with one piece of moderately priced furniture which 65 can be assembled in various ways as shown in the drawings, can suit the convenience of the owner, and can be a useful article both at night and during the day.

It is thought from the foregoing description 70 that the advantages and novel features of the invention will be readily apparent.

It is to be understood that changes may be made in the construction and in the combination and arrangement of the several parts 75 provided that such changes fall within the scope of the appended claim.

Having thus described my invention, what I claim as new is:—

A couch of the class described comprising 80 a pair of separate interfitting sections, each of L-shape in a horizontal plane, the lengths of certain corresponding limbs of each section being the same and their widths being the same as the lengths of the adjacent other 85 limbs.

In testimony whereof I affix my signature.

LAWRENCE B. WILSON.
